UNITED STATES PATENT OFFICE

151,688

DESIGN FOR AN AIRPLANE CONTROL TOY

Charles H. Foster, New York, N. Y.

Application August 5, 1948, Serial No. 147,947

Term of patent 14 years

(Cl. D34—15)

To all whom it may concern:

Be it known that I, Charles H. Foster, a citizen of the United States of America, residing at New York, in the county of New York, State of New York, have invented a new, original, and ornamental Design for Airplane Control Toy, of which the following is a specification, reference being made to the accompanying drawing forming part thereof.

Referring to the drawings, Fig. 1 is a front elevational view of an airplane control toy embodying my new design; Fig. 2 is a side elevational view; Fig. 3 is a side elevational view from the opposite side and Fig. 4 is a rear elevational view of the same on a reduced scale.

The dominant features of my design reside in the portions shown in full lines.

I claim:

The ornamental design for an airplane control toy, substantially as shown and described.

CHARLES H. FOSTER.
